SWITCH MECHANISM FOR PRESSURE-TYPE
ELECTRICALLY HEATED STERILIZER

Joseph W. Spradling and Pearl L. Engler, Madison, Wis., assignors to Air Reduction Company, Incorporated, New York, N. Y., a corporation of New York

Application February 12, 1952, Serial No. 271,198

6 Claims. (Cl. 219—38)

1

This invention relates to electrically heated surgical sterilizing apparatus and particularly to improved electric control switch mechanisms for sterilizers of the pressure type.

In electrically heated pressure sterilizers for surgical goods, the steam necessary to effect the sterilization of the goods is usually generated in a sub-boiler which is connected by suitable means with the sterilizer autoclave. Electrical heating coils are placed in the sub-boiler where steam is generated and then circulated through the autoclave pressure chamber. In order to produce the required sterilization temperature and maintain such temperature for the prescribed length of time, pressure responsive control means are incorporated in the control circuit of the heating coils through which the heating of the coils is controlled to maintain a predetermined steam pressure. As a precaution against damage to the heating elements it has been customary to provide a circuit cut-out switch which prevents operation of the heating coils when the water in the sub-boiler falls below a predetermined level at which the heating elements will become overheated.

Heretofore these types of electric control means have consisted substantially of separate independent devices remotely located on the sterilizer. This arrangement lacks compactness which would enable efficient use by the operator and involves a great number of bothersome fixtures and fittings. Such controls moreover usually incorporated relay devices in the circuit for control thereof in response to pressure and temperature conditions in the sterilizer. One of the disadvantages of relay devices resides in the necessity for designing different control circuits for A. C. and D. C. power sources which are not interchangeable. A further objection was found in the fact that control switch devices, of an otherwise suitable nature, were limited to a small selection of operating pressures which restricted the utility of such sterilizer apparatus.

It is therefore an object of the present invention to provide in pressure-type, electrically-heated sterilizers an improved electrical switch control mechanism including manual, pressure regulating, and low water cutout controls housed in a single compact unit.

It is a further object of the invention to provide such a compact control unit which is interchangeable as a control device for either A. C. or D. C. power supplies.

A still further object of the invention is to provide a single compact electrical control unit for pressure type sterilizers which is of improved

2

construction capable of affording a wide range of selected operating pressures and which will accurately maintain such pressures during sterilization.

A still further object of the invention is to provide an electrical control switch for electrically heated pressure sterilizers including manual, pressure regulating, and temperature responsive controls wherein electrical relay devices are not used and which is of adequate power capacity to be applied to sterilizers of substantially any commercially required installation.

In accordance with the invention, a surgical sterilizing apparatus including a pressurized sterilizing vessel and electric coil heating means, is provided with an improved compact control switch mechanism, comprising a switch housing having a liquid capsule switch element or elements pivotally mounted therein which are adapted to open and close the electric circuit of the heating coil means. Manual control means are associated with the switch elements to place the switch in operation and pressure responsive means in the switch housing are operatively connected with the switch elements for opening and closing the heating control circuit in response to fluctuations of pressure in said vessel to maintain a substantially constant sterilizing pressure. Temperature responsive means, in said housing are associated with the switch elements for opening the control circuit independently of the pressure responsive means when the temperature in the vicinity of the heating coil means exceeds a predetermined value. The switch elements are preferably mercury capsule switch elements which are in themselves well known and used in various switch devices. One or more of the switch capsule elements are used depending upon the amount of current that must be supplied to the control circuit and carried by the control switch.

Other objects and advantages of the invention will become apparent by reference to the following description and accompanying drawings in which:

Fig. 1 is a front elevation view of a surgical sterilizing apparatus embodying the invention;

Fig. 2 is a side elevation of the sterilizer shown in Fig. 1;

Fig. 3 is a front view partially in section of the switch device in Fig. 1 of the drawings;

Fig. 4 is a sectional view taken along the line 4—4 in Fig. 3 looking in the direction of the arrows;

Fig. 5 is a sectional view taken along the line 5—5 in Fig. 4 looking in the direction of the arrows;

Fig. 6 is a schematic perspective illustration of the control switch linkage and cam mechanism. Referring now to the drawings, a pressure type sterilizer is shown at 10 in Figs. 1 and 2. The sterilizer consists of an autoclave 12 supported in a frame 14 and a sub-boiler 16 from which steam is supplied for sterilizing goods placed in the vessel 12. The vessel has a door closure 17 of the usual construction through which such articles may be inserted. The autoclave is substantially identical in construction to one type commonly used comprising an inner shell 18, defining an inner sterilizing chamber 20, and an outer shell or jacket 22 which creates a closed space 24 around the inner shell 18. The sub-boiler 16 is connected with the autoclave by means of coupled pipe connections 26. Steam generated in the sub-boiler is delivered through the pipes 26 to the space 24 between the inner and outer sterilizing vessel shells. A pipe 28 opens through the outer shell 22 and delivers the steam, substantially free of condensate, from the space 24, through a steam control valve 30 and pipes 32 and 34 to the inner sterilizing chamber 20. A drain 36 for the air and condensate is provided in the forward lower region of the inner shell 18 having a pipe 38 which connects with a steam exhaust line 40 through an air and condensation ejector 42. The exhausting of the chamber 20 is controlled by an exhaust valve 44, Fig. 1 which allows steam to be exhausted from pipe 28 through the exhaust pipe 40. Thus steam, from pipe 28, is passed through a horizontally disposed vacuum ejector device 46, the exhausting valve 44, and exhaust line 40. Fig. 2. The accompanying condensate is discharged into a drain pipe 48 having the usual air gap waste fitting 50. A negative pressure is produced by the ejector 46 in the pipes 32 and 34 which draws a vacuum within the chamber 20. The provision of such a vacuum accelerates the drying of the sterilized goods as is well known in the art. A fixture 52 is mounted at the top of the sterilizer autoclave including a safety relief valve and pressure gauges indicating respectively the pressure of steam in the sterilizing chamber and in the space between the inner autoclave shell and the jacket. A thermometer 54, Fig. 1, in the drain line 38 enables a comparison to be made between the temperature in the drain and the temperature of saturated steam at the pressure indicated on the pressure gauge of fixture 52 as a test for complete elimination of air as is well understood in the art.

Water is delivered to the sub-boiler through a water supply line 56 having a shut-off valve 58 which permits the boiler to be filled to a desired level as shown on the level indicator 60, Fig. 1. An electric resistance heating coil 62, extending substantially along the length of the sub-boiler, Fig. 2, and at the bottom thereof, provides the necessary heat to vaporize the water and supply steam for sterilization in the chamber 20. Although only a single coil 62 has been shown, it will be understood that additional coils may be used for sterilizers of larger capacity. The coil 62 is sealed in a water-tight manner in the front end plate of the sub-boiler and extends therethrough to receive suitable electrical connections in a control switch housing 64. The control switch is fastened to the end of the sub-boiler and is also secured by means of a clamp 66 to a cross-piece of the frame 14. The power for energization of the heating coil or coils is obtained from an A.-C. or D.-C. electric outlet through a power cord such as seen at 68 in Fig. 1. The electric

supply circuit of the heating coil or coils is completed by switch means in the control switch 64 which will be described hereinafter. A pressure tap line 70 is connected in the pipe 26 leading from the sub-boiler. The pressure in the line 26 is transmitted to pressure responsive means within the control switch housing which operates the control switch device to regulate the generated steam pressure. A temperature bulb 72 is disposed within the sub-boiler in close proximity to the heating coil which is responsive to excessive heating of the coil or coils 62 when the water falls below a predetermined safe level to open the control circuit.

The control switch device 64 may be briefly described as comprising in general one or more mercury switches attached to a rack such that the rack and mercury switches may be tilted to make or break an electric circuit or circuits through corresponding heating coil elements. The desirable features and advantages of the switch apparatus are found especially in the combination of means for operating, or tipping, the mercury switches. These are as follows:

First by manually turning a control camshaft with an attached off-on cam. The camshaft has an "operative" and an "inoperative" position. In the "inoperative" position of the cam shaft, the attached off-on cam is positioned against a portion of the mercury switch rack assembly causing the mercury switch rack to tilt such that the mercury switch or switches will be "off" and will remain "off" regardless of the operation of other component parts of the device. In this position the heating coil 62 may not be energized. In the "operative" position of the cam shaft, the attached off-on cam is positioned so that it will not engage the mercury switch rack. With the cam shaft in this position the mercury switch rack will assume a position, partly as an effect of a gravity bias acting on the mercury switch rack and partly because of the effect of a leaf compression spring, such that the mercury switches, independent of other forces acting thereon, will be "on." In this position the heating coil 62 may be energized.

A second means of tipping the mercury switch rack is as follows. With the aforementioned cam shaft and off-on cam so positioned that the off-on cam does not engage the mercury switch rack, "operative position," the mercury switch rack may be made to tilt to the "off" position or the "on" position as a result of an increase or decrease in the pressure within a spring loaded bellows made responsive to the steam pressure in the sterilizer chamber. The movement of the bellows is so compounded through a system of levers that tilting of the mercury switch rack is easily effected by the bellows action.

A third means of tipping the mercury switch rack becomes evident from the following explanation. A latching device is provided in conjunction with the cam shaft. It consists of a spring loaded cutout lever system with a stop pin that may engage a cutout cam, which is attached to the cam shaft, in either the "operative" or "inoperative" positions of the cam shaft. This lever system is actuated by a diaphragm capsule as a result of an excessive temperature rise in the vicinity of the cutout bulb 72 mounted adjacent to the heating coil 62 and connected by a tube to the diaphragm capsule. This latching device provides a means of locking the cam shaft in the "operative" position so the mercury switch rack may be tilted to the "on" or "off" positions. Fol-

lowing an excessive temperature rise in the vicinity of the cutout bulb, the diaphragm capsule expands and actuates the cutout lever system, positioning the lever system so that the cutout cam is disengaged from the latching device in the "operative" position of the cam shaft and cannot be engaged in the "operative" position. Therefore, under the action of a torsion spring, the cam shaft will seek the "inoperative" position and the mercury switch rack will be tilted to the "off" position. Hence, this mechanism provides another means of tilting the switch rack to the "off" position.

The mercury switches 73, Figs. 4 and 5, are of a well-known design and consist of a glass container 74 partly filled with mercury 76 and having two electrodes 78 and 80 in each mercury switch. Each mercury switch is rigidly attached to a switch rack 82 by spring clips 84. Electrical connections are made to each mercury switch by connecting the electrodes 78 and 80 with insulated wire 86 and 87 respectively as illustrated in Figs. 3 and 5. The insulated wires 86 and 87 attach to terminal blocks 88 and 90 to which suitable electrical connections may be made from the external electrical circuit, through the cord 68, Fig. 1. A pilot light assembly 92 may be provided to indicate the operation of the mercury switches.

It will be noted that the electrical connections for only one of the mercury switches are shown. Referring to Fig. 3, a conductor 94 connected on terminal block 88 is attached to a terminal connection 96 which is one end of the resistance heating coil 62. The other end terminal 98 of the coil receives a conductor 100 which is connected with a terminal box 102 fastened on the side of a frame 104 of the switch housing. A removable cover 105, a portion of which is shown in Fig. 3, conceals the inner switch frame 104. The terminal block 98 is connected with the terminal box by a conductor 106 completing the circuit connections for the single mercury switch and the heating coil 62. Thus when the mercury switch whose connections are shown is placed in "on" position the electric circuit is completed through the coil 62. It will be seen that the terminal ends of second and third heating coil elements appear in Fig. 3 shown at 108 and 110. Thus the second and third mercury switches 73 may be connected respectively with the corresponding heating coil elements as described for the first 50 mercury switch to provide additional heating capacity. It is preferable that each of the mercury switches and corresponding heating coil units be connected in parallel with each other to divide the total current load and thus reduce the current passed through any single mercury switch. By providing a suitable number of such electrically parallel connected mercury switches a control switch of any required capacity may be provided without exceeding the capacity of a single one of the mercury switches.

Figs. 4, 5, and 6 show the manner in which depending side arms 83 of switch rack 82 are mounted on pivot pins 112 and 113, which are rigidly attached to a switch carriage 114 and provide a center of rotation for the switch rack 82. Pivot pins 116 and 118 are rigidly attached to the switch carriage 114 and may rotate within bearing holes not shown in the frame 104. Stop pins 120 and 122 are rigidly attached to the switch carriage 114. Notches 123 and 123' are provided in the switch rack 82 to provide limit stops for the stop pins 120 and 122.

An operating shaft 124, shown in Figs. 4, 5, and 6, is supported at each end of the frame 104

through suitable bearing holes in the frame. A cutout cam 126 and an off-on cam 128 are rigidly attached to the shaft 124. These cams 126 and 128 are mounted in parallel planes perpendicular to the axis of the cam shaft 124. A torsion spring 130, Figs. 4 and 6, is wound about the shaft 124 with one end being securely fastened to the cam shaft and the other end to the frame 104 as shown at 132, Fig. 6. The bias offered by the torsion spring 130 causes the shaft to seek and position itself in the "inoperative" position unless held in the "operative" position by the cutout cam 126, as will become evident when the cutout lever system is explained.

A cutout lever 134, which may be turned about a cutout pivot pin 136 that is rigidly attached to a portion of the frame 104, has a cutout stop pin 138 rigidly attached thereto. The cutout stop pin 138 may engage the cutout cam 126 in the "operative" position of the control shaft 124 as illustrated in Figs. 4, 5, and 6, if the cutout lever 134 is properly positioned, and it may engage the cutout cam in the "inoperative" position of the shaft regardless of the position of the cutout lever within the limits of its normal movements. The stop 140 and the catch 142 of the cutout cam 126, which are engaged by the stop pin 138 in the "inoperative" and "operative" positions respectively of the operating shaft 124, are indicated clearly in Fig. 6.

A rack finger 144 is securely fastened to the switch rack 82 and may be engaged by the off-on cam 128 when the cam operating shaft 124 is turned to the "inoperative" position in which the switch control is turned off.

One end of a compression spring 146 rests against a bent portion 152 of the frame 104 and the other end exerts a force against the cutout lever 134 such that it tends to revolve the cutout lever and cutout stop pin 138 into a position so that the cutout stop pin can engage the cutout cam 126.

A cutout plunger 148, which is constructed so that a portion of it passes through a hole 150 in the cutout lever 134 and through guides 152 constituting bent portions of frame 104, has a part of its cross section of a greater diameter than the hole 150 so that the cutout plunger 148 seats against the cutout lever 134 adjacent to the hole 150.

As shown in Figs. 4 and 5, a thermal sensitive low water cutout of a well-known design is provided as a component part of switch mechanism. The low water cutout consists principally of a diaphragm capsule 154 which is connected by a tube 156 to the thermally-responsive bulb 72 mounted in the sub-boiler as seen in Fig. 2. The bulb 72 is filled with a liquid that vaporizes when heated. A diaphragm stud 158 is rigidly fastened to one face of the diaphragm capsule and a threaded stud 160 is fastened to the opposite face of the diaphragm capsule. A nut 162 that fits the threads of the stud 160 fastens the low water cutout assembly to a bracket 163 secured on frame 104. The diaphragm stud 158 may engage the cutout plunger 148 when the diaphragm capsule 154 expands. The force that the diaphragm capsule and the diaphragm stud 158 may exert against the cutout plunger 148 is sufficient to overcome the force of opposition offered by the compression spring 146. Hence, an excess of heat in the vicinity of the cutout bulb 72 will result in the cutout lever 134 being rotated about the cutout pivot pin 136 against the force offered by the compression spring 146 and the cutout stop

pin 138 will be positioned so that it can not engage the catch 142 of the cutout cam 126.

A bellows 164 is hermetically sealed to a bellows head 166 which in turn is rigidly fastened to the frame 104. A tapped opening 168 in Fig. 5, in the bellows head 166, allows the tap line 70, Fig. 1, to be attached thereto for the purpose of communicating a change in pressure in pipe 26 to the bellows 164. An actuating head 170 seats against the bellows as shown in a cutaway section of Fig. 4. One end of a compression spring 172 seats against the collar 173 of the actuating head 170 and the other end seats against a yoke 174, as a cutaway section of Fig. 4 illustrates. The yoke 174 has lugs 175 which are in threaded engagement with a pair of adjusting screws 176 and 178 as shown in a cutaway section of Fig. 5. The adjusting screws 176 and 178 are mounted through a bearing in a plate 180 on the frame 104 and are rigidly attached to gears 182 and 184 respectively, as seen in Fig. 4.

Another gear 186 is rigidly attached to the adjusting screw 178 and gear 184, Fig. 4. The purpose of the gear 186 is to turn a gear train to a pointer 187 of dial 188, Fig. 1, to give an indication of the position of the yoke 174. The position of the yoke 174 with respect to the adjusting screws 176 and 178 determines the amount that the compression spring is compressed and predetermines the amount of pressure within the bellows 164 that will cause the actuating head 170 to overcome the force offered by the compression spring 172 and to compress the compression spring, allowing movement of the bellows head.

A gear 188 engages the gears 182 and 184 and is rigidly attached to a shaft 190, which is free to turn in a bushing 192 fitted in the frame 104. Turning the shaft 190 causes the adjusting screws 176 and 178 to rotate at the same rate and in the same direction with respect to the frame 104. Therefore, the yoke 174 will experience uniform advancement on the adjusting screws.

A pair of side lever arms 194 and 196 are rigidly attached to a crosspiece 198 to form a single rigid link 200. Two pivot pins 202 and 204 are rigidly attached to the frame 104 and fit into bearing holes in the crosspiece 198. The side lever arms 194 and 196 and the crosspiece 198 are turned as a unit about the pivot pins 202 and 204 by the force of two pivot pins 206 and 208, which are securely attached to the actuating head 170, acting in slots 210 and 212 in the side lever arms 194 and 196. The motion of the side lever arms is transferred to the switch carriage 114 by two switch pins 214 and 216 which fit into slots 218 and 220 in the side lever arms 194 and 196. This construction is readily seen by referring to Fig. 4 and Fig. 6.

Two stop pins 222 and 224, which are rigidly attached to the switch carriage 114, allow the switch carriage to rotate about the pivot pins 116 and 118 within the limits established by the contact of the stop pins with the outline of the two limit holes 226 and 228 in the frame 104.

One end of a leaf compression spring 230 fits into a notch 232 in an ear 234, which is rigidly attached to the frame 104, and the other end fits into a notch 236 in the stop pin 224. The leaf compression spring 230 assures positive action of the mercury switches when the pressure in the bellows 164 is sufficient to overcome the compressive force of the compression spring 172. The leaf compression spring causes a biasing force against the stop pin 224 such that it will tend to tilt the switch carriage 114 and aid the force

exerted by the side lever arms 194 and 196 on the switch carriage 114 and to act either with or against the gravity bias acting on the switch carriage depending upon which side the center of the stop 224 is on the line of centers through the pivot pin 118 and the stop pin 224.

Our invention in actual operation for controlling the operation of an electrically heated steam sterilizer such as sterilizer 10 would operate as follows.

The attendant for the sterilizer would turn on the electric power supply to the sterilizer and adjust the water level in the sterilizer boiler to the proper level. The control device would be put in operation by turning the pressure adjusting knob 238 until the desired operating pressure (and consequently temperature if the steam remained saturated) is indicated on the dial 188. Rotation of knob 238 acts through the gear train 188, 182, 184 and 186, moving the indicator 187 of dial 188 and causing rotation of the threaded shafts 176 and 178, Fig. 4. This adjustment sets the operating pressure of bellows 164. The knob 240, Figs. 1 and 2, is operated to rotate cam shaft 124 to the "operative" position and the mercury switch, or switches, are thus allowed to tilt to the "on" position closing the electric circuits to the heater elements.

As the heat from the heater elements is transferred to the water in the boiler, the temperature of the water increases and a vapor pressure develops in the sub-boiler 15 and autoclave 12. When the desired operating pressure within the sterilizer chamber is reached the bellows 164 expands, thereby compressing the compression spring 172 and causing the actuating head 170 to move and this motion to be transmitted through the lever system to the switch carriage 114; if the pressure continues to increase and exceeds the preset operating pressure, the switch carriage 114, the switch rack 82, and the mercury switches are tilted to the "off" position so that the mercury switches are non-conducting, hence shutting off the power to the heating elements. As radiation and convection carry the heat away from the boiler and sterilizer, the vapor pressure diminishes within these chambers and within the bellows 164. When the pressure in the bellows decreases below the value that the dial or pointer system had been previously set at plus a slight differential determined by the physical characteristics of the leaf compression spring 230 and by the gravity bias acting on the switch rack 82 and the switch carriage 114, the compression spring would compress the bellows and cause the actuating head 170 to move. This motion would be transmitted through the lever system to the switch carriage 114 causing the switch carriage, the switch rack, and the mercury switches to tilt to the "on" position. This cycle of operation would continue until the operator manually turned the cam operating shaft to the "inoperative" position, or the low water cutout operated.

In the event that the water level within the steam sub-boiler would fall to a level such that sufficient water was not present to effectively carry the heat away from the heating elements, the temperature of the heating elements and of the low water cutout bulb 72, mounted adjacent to the elements, would increase abnormally. This would cause a vapor pressure to be transmitted from the cutout bulb, through the connecting tube 156 to the diaphragm capsule 154. The diaphragm capsule would expand so as to cause the diaphragm stud 158 to engage and actu-

ate the cutout plunger 148, forcing the cutout lever 134 to turn against the force of the compression spring 146. This in turn would result in a repositioning of the cutout stop pin 138 so that the cutout cam 126 could not engage the cutout stop pin in the "operative" position of the operating shaft 124. Therefore, if the cam shaft 124 were positioned in the "operative" position it would be released and by the action of the torsion spring 130 would turn to the "inoperative" position of the control shaft in which energization of the heating elements through the switch mechanism is not possible. Until the temperature in the vicinity of the cutout bulb 72 diminished, the cutout stop pin 138 could not engage the cutout cam to retain the shaft 124 in "operative" position and the switches can not be closed.

It will now be seen that a preferred embodiment of an improved sterilizer apparatus and electric switch mechanism therefor, embodying several of the features and advantages of the invention hereinbefore mentioned has now been described. The invention is not limited to the specific embodiments herein illustrated and described, but may be used in other ways without departure from its spirit as defined by the following claims.

We claim:

1. An electrically heated sterilizer comprising a frame mounted pressure vessel having a chamber, a water supply inlet, means including an electric heating coil in said chamber and an electric circuit therefor for generating steam and maintaining steam pressure therein, and a unitary control switch mechanism housed in a switch box supported by said frame, said switch mechanism comprising switch elements operable between "on" and "off" positions to complete or break, respectively, said circuit to said electric heating coils, said switch elements being biased toward "on" position to complete said circuit, manually adjustable means movable to "inoperative" and "operative" settings, said manual means being biased toward "inoperative" setting and adapted in said "inoperative" setting to dispose said switch elements in "off" position, temperature responsive detent means including a portion extending from said housing and disposed in the vicinity of said heating coils, said detent means being normally operable to retain said manual means in "operative" setting and responsive to a predetermined temperature of said heating coils to release said manual means, pressure responsive means, means connecting said chamber with said pressure responsive means, and linkage members operatively connecting said pressure responsive means with said switch elements to produce movement of said elements completing or breaking said heating coil circuit to maintain a desired chamber pressure when said manual means is in "operative" setting.

2. A sterilizer apparatus substantially as set forth in claim 1 wherein said switch elements are

carried by a common supporting rack means adapted to be moved to place said switch elements in "on" and "off" positions and said manual and pressure responsive means are operatively connected with said supporting means.

3. A sterilizer apparatus substantially as set forth in claim 2 wherein said switch elements comprise at least one mercury capsule and said means operatively connecting said pressure responsive means and said supporting means comprise a linkage system including an off-centering mechanism effective on either side of a neutral center position of said linkages to urge said linkages away from said center position to thereby assist the regulating effort of said pressure responsive means.

4. A sterilizer apparatus substantially as set forth in claim 3 wherein said pressure responsive means comprises an expansible bellows, said linkage system includes a carriage pivoted in said housing adapted to be rotated by said bellows, said switch supporting rack being pivotably mounted in said carriage, said carriage having means thereon for causing said rack to be rotated with said carriage, said rack being adapted for rotation to "off" position by said manual means independently of said carriage, and said off-centering mechanism is supported by said switch housing and acts upon said carriage.

5. A sterilizer apparatus substantially as set forth in claim 4, having a resilient member disposed to act against said bellows and means for adjusting the force exerted thereby against said bellows to thereby set the operating pressure of the sterilizer.

6. A sterilizer apparatus according to claim 1 wherein said pressure vessel includes an autoclave and a sub-boiler connected thereto by pipes, said water inlet being adapted to supply water to said sub-boiler, said heating coils forming a part of said switch box housing extending outwardly therefrom and disposed in the lower region of said sub-boiler, said switch box housing being mounted on said sub-boiler and having gasket sealing means therebetween through which said coils extend into the sub-boiler and said temperature responsive means disposed in the vicinity of said heating coils being responsive to a predetermined temperature occurring in the absence of an adequate water supply level to actuate said detent means and prevent setting said manual means in "operative" position.
